GUIDING ACTION FOR BRASS MUSICAL AND OTHER INSTRUMENTS

Filed Nov. 16, 1935

UNITED STATES PATENT OFFICE

2,111,967

GUIDING ACTION FOR BRASS MUSICAL
AND OTHER INSTRUMENTS

Nathan Einhorn, Philadelphia, Pa.

Application November 16, 1935, Serial No. 50,072

9 Claims. (Cl. 84—392)

In my prior Patent No. 2,003,995, of June 4, 1935, I have described and broadly claimed a novel guiding action for various valves and slides for musical, brass and other instruments.

5 In my present invention, I have increased the efficiency of the guiding and anti-friction action of reciprocating or revolving valves and of slides.

A further object of the invention is to devise 10 novel means for adjusting the anti-friction rollers, which may be metallic or non-metallic material, such as rubber or fiber.

15 A further purpose of this invention is to devise in conjunction with a slide, guided as herein set forth, a novel construction of tube, slide and amplifier which progressively increases in cross section towards the amplifier.

20 With the above, and other objects and purposes as will be hereinafter clearly set forth, my invention comprehends novel guiding actions and 25 mountings for moving parts such as valves and slides for brass, musical and other instruments.

Other novel features of construction and advantage will hereinafter more clearly appear in the detailed description and the appended claims.

25 For the purpose of illustrating the invention I have shown in the accompanying drawing, typical embodiments of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

30 Figure 1 is a sectional elevation of a valve, embodying my invention.

Figure 2 is an enlarged section of a portion of Figure 1.

Figure 3 is a top plan view of Figure 2.

35 Figure 4 is a section on line 4—4 of Figure 1.

Figure 5 is a section on line 5—5 of Figure 4.

Figure 6 is a sectional view on an enlarged scale of a portion of Figure 1.

40 Figure 7 is a top plan view of the upper cap seen in Figure 1.

Figure 8 is a sectional elevation of another embodiment of a valve.

Figure 9 is a sectional view of a guiding action seen in Figure 10.

45 Figure 10 is an elevation partly in section of a trombone.

Figure 11 is a view of one end of the guiding action seen in Figure 9 with a cover removed.

50 Figure 12 is a view of the other end of the

guiding action seen in Figure 9, with the juxtaposed cover removed.

Figure 13 is a sectional view on an enlarged scale of a novel pivot mounting for an anti-friction member.

5 Figure 14 shows an adjustable pin mounting for an anti-friction member.

Figure 15 is a section of a rotary valve.

10 Figure 16 is a top plan view of another embodiment of valve cap.

Similar numerals indicate corresponding parts.

Referring to the drawing:

Referring first to the embodiment seen in Figure 1, 1 designates a valve casing in which is mounted a reciprocating tubular valve 2. The 15 valve 2 carries a plate 2'. This type of valve mechanism is especially adapted for use with a cornet, trumpet or Fluegel horn. The upper end of the valve casing is closed by a threaded cap 3 having air relief openings 4 and the lower end of the valve casing is closed by a threaded bottom member 5 having air relief openings 6. These 20 openings may have any desired contour and may be curved as shown in Figures 1 and 7 or as shown at 7 in Figure 16 in which case a central bar 8' forms a bearing for the valve stem 9. 25

The valve stem 9 as shown in Figure 1 has its lower end in threaded engagement with the valve and its upper end is internally threaded to receive the threaded shank of the pressure 30 piece 10.

35 The valve 2 is provided with the necessary valve openings 11 for registering with the slides for producing various notes when playing a musical number.

The anti-friction devices at each end of the valve are in the form of rollers 12 free to revolve. These rollers are made of any suitable material and may be of metallic or non-metallic material such as for example fiber, rubber or the like. 40 These rollers 12 are mounted in shoes 13 cylindrical in cross section and cut away to receive the rollers which are free to revolve on pins 14, secured to the forward ends of the shoes. The shoes are adjustable in cylindrical openings 15 45 in the valve caps 21 which are slotted at 16 to receive screws 17 having flat washers 18 between their heads and the valve. A plurality of rollers are employed at each end of the valve and their positions can be readily adjustable so that they 50 will have the proper contact with the inner cylindrical wall of the valve casing 1. A shouldered screw 19 at the valve bottom has its lower end tapered to receive a spring 20.

The upper end of the valve casing has a lining 55

sleeve 21 having a vertical slot 22 into which extends a roller 23 which rides on the side walls of the slot to prevent relative rotation of the valve and cylinder. The roller 23 is mounted on a bearing pin 24 which passes through a washer 25 and is threaded into a rod 26 through which the valve stem passes and to which it is fixed by a pin 27. Each end of the bar extending from the valve stem is covered by a tubular felt washer 28. The felt washers are larger than the roller to serve as a cushion on the upward stroke of the valve without creating a suction. The felt washer opposite the roller is retained on its rod by a screw and washer 29, see more particularly Figures 2 and 3.

In Figure 8, I have shown an improved type of valve for different instruments such as a baritone, tuba, cornet, trumpet or alto.

In this embodiment of valve, the rollers 30 are 20 radially adjustable in end members secured in the valve at opposite ends and the valve wall is cut out at 31 to receive the rollers.

The cylinder is provided with a desired number of relief openings 32 to prevent a suction by the 25 movement of the valve.

In Figures 9, 10, 11 and 12, I have shown an improved guiding action for any slide instrument, for example a trombone.

A flanged disc or carrying member 32 is fixed 30 to a slide such as 33 and has end caps 34. The member 32 has slots 35, see Figure 12, to receive screws 36 which engage the roller brackets 37 which are slotted to receive the rollers 38. Each bracket has a screw 39, the tapered head of which 35 is countersunk in the outer periphery of the disc 32 and inwardly of the flange of the disc, it has fixed to it a collar 40, so that the rotation of a screw 39 will move its roller inwardly or outwardly to give it the proper contact with the inner 40 tube 41. The roller may have pivot trunnions 42 engaging pivot screws 43 as in Figure 13 or the roller may be mounted on a bearing screw 44 as in Figure 14.

The trombone has a slide 45, see Figure 10, 45 into which the tube 29 telescopes and one leg 46 of the slide terminates at 47 while its other leg 48 telescopes into the tube 49 terminating at 50. The leg 48 is longer than the leg 46 and terminates at 51 telescoping into the tube 52. By this 50 construction, the fixed tubes and the slide progressively increase in cross sectional area from the mouth piece to the bell of the horn.

In Figure 15 I have shown a guiding action for a rotary valve which can be advantageously employed with a French horn, baritone, tuba, cornet, Fluegel horn or trumpet.

The valve casing 53 has end caps 54 secured to it by screws 55. The valve may have pivot trunnions 56 engaging pivot screws 57 in a cap as shown at the left end of Figure 15 or pivot pins 58 threaded into an end cap may engage the walls of a bearing recess 59 in the end of the valve. In such case the end cap preferably has a threaded boss to receive a recessed closure 60. The arm 61 for partially rotating the valve has a rod 62 connected with the valve and passing through a curved recess 63 in its end cap. The rotary valve may be actuated by the conventional cord, if desired, to effect its partial rotation.

The trombone may have the braces 64, 65 and 70 66, and the slide preferably has a revoluble grasping sleeve 67 mounted on a rod 68.

The air passing through the trombone is always passing into a larger cross sectional area

which produces a better tone. By making one leg of the slide longer than the other, the slide is more easily assembled, and by mounting the guiding actions as shown there is no drag or sag when the slide is moved to seventh position.

The guiding actions on the trombone are arranged in a novel manner. Two of them are on the movable element and two of them are on the stationary element so that friction is eliminated during the entire stroke of the slide.

The legs of the slide at their inner ends are not braced together so that they are free to adjust themselves in telescoping relation with the tubes, and by having the handle rotatably carried by only one leg of the slide a free sliding 15 action is obtained.

In the valve seen in Figure 8, the valve casting is slotted, as at 69 to receive a roller 70 carried by the valve and engaging the side walls of the groove to prevent relative rotation of the 20 valve and its casing.

The valve in Figure 1 has a floating action, as the conventional suction producing cushion on the valve stem is eliminated and air can pass freely through the valve and from the ends of the 25 casing to the atmosphere.

The standard clearance in valves and slides has been a few thousandths of an inch. In accordance with this invention, this clearance can be materially reduced and the adjustable rollers will hold the movable and stationary elements out of contact with substantially less than standard clearance, so that there is a free and unrestricted movement of the valves or slides.

It will be apparent that as the parts wear, the 35 rollers can be adjusted to give the same frictionless condition between the relatively movable parts as they had originally, thus producing an action which will be efficient for a longer period of years.

The action is much easier to work. No lubrication is necessary. One can play with more life and velocity, finer phrasing and cleaner technique.

It will now be apparent that I have devised a 45 new and useful guiding action for valves and slides of brass musical and other instruments which embodies the features of advantage enumerated as desirable in the statement of the invention and the above description, and while I 50 have, in the present instance, shown and described preferred embodiments thereof which will give in practice satisfactory and reliable results, it is to be understood that these embodiments are susceptible of modification in various 55 particulars without departing from the spirit or scope of the invention or sacrificing any of its advantages.

Having thus described my invention, what I claim as new and desire to secure by Letters Patent is:

1. In a guiding action for brass musical instruments, a valve casing having a longitudinally extending slot, a reciprocatory valve in said casing, and a roller carried by said valve and free 65 to revolve in said slot with its periphery engaging opposite walls of said slot to prevent relative rotation of the valve and casing.

2. In a guiding action for brass musical instruments, a valve casing, a valve in the casing having a stem, means to prevent relative rotation of the valve and casing, a member carried by and extending transversely of said stem, and tubular cushioning elements on said member.

3. In a guiding action for brass musical instru- 75

ments, a valve casing, a reciprocatory valve in the casing, guides at an end of said valve, shoes in said guides, rollers free to revolve in said shoes, and means to adjust said shoes to provide surface engagement of the rollers with the casing and to hold adjacent surfaces of said valve out of contact with said casing.

5 4. In a guiding action for brass musical instruments, a valve casing, a reciprocatory valve in the casing, guides at each end of said valve, shoes in said guides, rollers free to revolve in said shoes, and means to adjust said shoes to provide surface engagement of the rollers with the casing and to hold adjacent surfaces of said valve out of contact with said casing.

10 5. In a guiding action for brass musical instruments, a valve casing, a reciprocatory valve in the casing, guides at an end of said valve, shoes in said guides, rollers free to revolve in said shoes, means to adjust said shoes to provide surface engagement of the rollers with the casing and to hold adjacent surfaces of said valve out of contact with said casing, and means to lock said shoes in their adjusted position.

15 25 6. A guiding action for valves of brass musical instruments, comprising a valve casing, a reciprocatory valve in said casing, guides carried by said valve, shoes adjustable in said guides, pivot bearings carried by said shoes, and rollers free to revolve in said pivot bearings, and having only sur-

face engagement with the walls of the valve casing to hold adjacent surfaces of said valve and casing out of contact.

7. In a guiding action for slides of brass musical instruments, a movable and a stationary element in telescopic relationship, a mounting on one of said elements, roller brackets adjustable on said mounting, means to fix the brackets in adjusted position, and rollers mounted in said brackets to have surface contact with the adjacent wall of the other element only to thereby hold adjacent walls of said elements out of contact.

10 8. In a brass musical instrument, stationary and movable elements in telescopic relationship, and two guiding actions on each element, each of said actions including rollers adjustably carried by one element and having only surface engagement with the other element.

15 9. In a guiding action for brass musical instruments, a valve casing, a reciprocatory valve in the casing, guides at one end of said valve, shoes in said guides, rollers free to revolve in said shoes, means to adjust said shoes to provide only surface engagement of the rollers with the casing, a headed fastening device at one end of the valve and a spring carried by the head of said fastening device to be disposed in the plane of axial movement of the valve.

20 25 NATHAN EINHORN. 30
